VALVE ATTACHMENT

Steve E. Olenick, Chicago, Ill., assignor to Boyle
Motor Products Company, Chicago, Ill., a cor-
poration of Illinois

Application August 14, 1933, Serial No. 684,961

4 Claims. (Cl. 123—90)

This invention is particularly applicable to internal combustion engines having overhead valves or valves operated by means of rocker arms. In the more common forms of construction, the rocker arms engage directly with the tops of the valve stems. The valve stems are confined to a vertical or rectilinear movement while the end of the rocker arm has a circular or pendular movement. As a consequence there is a constant tendency of the rocker arm to push or draw the end of the stem away from its axial movement with the result that the engaging portion of the rocker arm is frequently worn to a considerable degree which accentuates the thrust and often 15 the end of the valve stem is likewise worn, the relative wear depending upon the character of the two metals.

I have also found that in many automobile engines the lubricating oil is carried out to the end 20 of the rocker arm and flows down over the valve stem. While this is not objectionable for the intake valves, it is frequently exceedingly objectionable for the exhaust valves as the oil will tend to bake or harden on the hot valve stems thereby causing them to stick in the guides.

The objects of the present invention are particularly to provide means for overcoming the objectionable features above noted and particularly to provide a side thrust eliminator for overhead 30 valves. Other objects are to provide simple and efficient attachments or devices which may be readily applied in the manufacture of an engine or which may be utilized in connection with various types of engines having overhead valves; to provide a simple and efficient means for eliminating side thrust on valve stems and guides on overhead valve motors; to provide a universal joint or connection between the rocker arm and the valve stem to permit the valve stem to travel 35 through the center of the guide; to provide an attachment which may be applied without change in the rocker arm; to provide means for directing the oil away from the top of the valve stem of an exhaust valve; and to provide such other novel 40 features and advantages as will appear from the following description.

In the accompanying drawing illustrating this invention:

Figure 1 is a sectional view illustrating a valve 50 and rocker arm with one form of my attachment applied thereto;

Figure 2 is a view similar to Figure 1 with parts broken away and showing a modified form of construction; and

Figures 3, 4, 5 and 6 are detail views showing

further modifications or different embodiments of the invention.

In the arrangement shown in Figure 1, 7 represents a portion of an overhead valve engine body having a valve stem guide 8. The valve 9 has a stem 10 which projects upwardly through the guide and is held in normally closed position by the usual spring 11 which is connected with the stem 10 by means of my improved tension equalizer or spring retainer 12. This equalizer has a 10 spring engaging portion with a substantially conical center which engages with a tapered collar 13 which in turn embraces the sections of split annular key 14 which fits in a groove 15 in the stem. While there usually is some space between 15 the ends of the sections of the split key 14, it will be noted that the collar or bushing 13 fits tightly in the conical spring retainer 12.

The valve is adapted to be actuated by any suitable rocker arm as indicated at 16, the curved 20 end or contact portion of which is normally engaged with the valve stem. The rocker arm is shown as being pivoted on a shaft 18 and is actuated by a push rod 19 in the usual manner.

In order to avoid the side thrust above referred 25 to, I provide a cap 20 which fits closely over the upper end of the stem 10, the top of the cap being pointed or provided with a conical engaging surface 21. A second cap or flanged disc 22 is interposed between the cap 20 and the end 17 of 30 the rocker arm. The under surface of this cap is preferably dished or conical but at a less angle than the cone 21 so that it will tend to remain centralized thereon but at the same time may rock freely thereon. The outer flange or rim 23 35 projects downwardly over the cap 20 and prevents the disc or thimble 22 from being disengaged.

It will be particularly noted that the disc or thimble 22 is of larger diameter than the sleeve 40 or ring 13 so that any oil passing from the end of the rocker arm will be deflected outwardly over the sleeve and thus be prevented from running down on the valve stem. Although this arrangement is intended particularly for exhaust 45 valves, the cap 22 may be reduced in size for intake valves so that the oil may pass down along the valve stem in the usual manner.

In the modified form of construction shown in Figure 2, which is particularly intended for use 50 in the manufacture of new engines or new installations, the valve stem 24 has a conical upper end 25 which serves as a bearing for the conical under surface of the disc or cap 26 which is 55

interposed between the same and the end 17 of the rocker arm.

The arrangement shown in Figure 3 includes a valve stem 27 having a beveled or chamfered upper end 28. The cap or thimble 29 has an annular beveled portion 30 which rests on the beveled end 28 so as to make a sliding or rocking contact between the cap and the sleeve so that the cap will rock or move relatively to the stem due to the action of the contact portion of the rocker arm.

The valve stem 31 shown in Figure 4 has a cap 32 fitting over the end thereof with a central recess 33. The auxiliary cap or thimble 34 has a projection 35 fitting in the recess 33 whereby a knife or point contact is made so that the auxiliary cap 34 may swing freely on the end of the stem as the rocker arm 16 actuates the same.

Figure 5 discloses a stem 36 having a cap 37 with a central protuberance or bearing 38 which engages with a recess 39 in the auxiliary cap 40.

The arrangement shown in Figure 6 has a stem 41 with a hole or recess 42 for receiving a ball 43 which engages with a recess 44 in a cap or thimble 45 which is interposed between the ball and the rocker arm as shown.

It will be noted that with all the different forms shown, the rocking or vibration of the rocker arm will be transmitted to the valve stem through means providing a substantially universal joint whereby the valve stem may move freely up and down without any appreciable side thrust. This will minimize or obviate the lateral binding and wear of the stems and guides so that the valves will always be in proper position to seat correctly on the valve seats. By means of this arrangement a large amount of the troubles inherent in overhead valve engines will be avoided and the inter-position of the auxiliary cap or caps will further tend to prevent noise as well as to prevent wear on the end of the stem and the coating part of the rocker arm. While I have illustrated a number of forms of my invention it

will be observed that other changes or provisions may be made to adapt the same for different types of engines and therefore I do not wish to be limited to the particular arrangement herein shown and described except as specified in the following claims, in which

I claim:

1. The combination with the usual valve stem and rocker arm of an engine, of a cap engaging with the end of a valve stem and having a converging upper surface, and an auxiliary cap adapted to engage with the first named cap and with the contact end of the rocker arm, said auxiliary cap being adapted to rock on the first named cap. 15

2. The combination with a vertical valve stem and its actuating rocker arm, of a cap engaging with the upper end of the valve stem and having a conical upper surface, a thimble between the cap and the rocker arm, said thimble having a conical lower surface, the thimble being of sufficiently large diameter to direct oil away from the valve stem a sufficient distance so that the oil will not run down the same. 20

3. The combination with the usual valve stem and rocker arm of an engine, of a pair of coating elements adapted to be inserted between the stem and the arm in operative position, one of said elements comprising a cap fitting closely over the end of the stem and the other element comprising an auxiliary cap having rocking contact with the first named cap, the sides of said auxiliary cap extending downwardly a sufficient distance to maintain the same in position, and the top being flat for engagement with the rocker arm. 35

4. The combination with an engine having a valve stem and a rocker arm coating with the stem, of a cap fitting over the end of the stem, and a second cap engaging with the rocker arm in alignment with the stem and coating with the first named cap and providing relative movement therebetween. 40

STEVE E. OLENICK.
